UNITED STATES PATENT OFFICE.

ALBERT H. MITTAG, OF SCHENECTADY, NEW YORK, ASSIGNOR TO GENERAL ELECTRIC COMPANY, A CORPORATION OF NEW YORK.

SYSTEM OF DISTRIBUTION.

Application filed July 13, 1923. Serial No. 651,399.

My present invention relates to systems of electrical distribution in which it is desired to change direct current of one voltage to direct current of another voltage.

5 In a copending application of Ernst F. W. Alexanderson, Serial No. 651,409, filed concurrently herewith, there is described a system of this type in which electric valves are employed for controlling the supply of 10 direct current to the converting system.

In the operation of such a system with electric valves there are two requirements necessary for the most efficient and satisfactory operation. One of these is that the 15 control means should be operated in such a way that current will start to flow through one valve before it is completely interrupted in the preceding valve. Another requirement is that the current should be controlled 20 in such a way that substantially rectangular wave form impulses of current shall be supplied by each valve. When thermionic valves are employed the operation may also be improved by supplying to the control 25 means substantially rectangular wave form impulses of voltage.

The object of my invention is to provide 30 means whereby the above mentioned operating requirements may be efficiently obtained.

The novel features which I believe to be characteristic of my invention are set forth with particularity in the appended claims. My invention itself, however, both as to its 35 organization and method of operation, together with further objects and advantages thereof, will best be understood by reference to the following description taken in connection with the accompanying drawing in 40 which Fig. 1 shows diagrammatically one circuit connection which may be employed in carrying my invention into effect, and Fig. 2 shows a slight modification of one portion of the circuit connections.

45 I have indicated in Fig. 1 a system in which direct current from the mains 1 and 2 is supplied through the plate circuits of the thermionic valves 3 and 4 to the primary winding 5 of a transformer having a secondary winding 6, the opposite terminals of which are connected to the anodes of a mercury rectifier 7. Direct current main 1 connected to the middle point 8 of winding 5 and main 2 is connected to the cathodes of 50 55 the valves so that current impulses supplied

to the winding 5 by the two valves flow in opposite directions through winding 5.

The valves are controlled in the desired manner by means of voltage applied to their grids which are supplied from the secondary 60 winding 6. The connections for this purpose include a transformer 9 the primary of which is connected across the terminals of winding 6. The terminals of the secondary of transformer 9 are connected to the grids 65 of valves 3 and 4 through resistances 10 and the mid-point of the secondary of transformer 9, is connected to the cathodes of valves 3 and 4 through a reactance 11 and a resistance 12. 70

A load circuit to which the rectified current from rectifier 7 is supplied is connected from the middle point of secondary winding 6 through the load devices 13 to the cathode 14 of rectifier 7. Current for heating the cathodes of valves 3 and 4 may be supplied by means of a transformer 15 the primary of which is connected to the terminals of secondary winding 6. 75

In starting the operation of the system 80 described, current may first be supplied to the cathodes of valves 3 and 4 from a battery 16, by means of the switch 17. Direct current may then be supplied to the valves by means of the switch 18 which is first 85 closed upon contact 19 in order that resistance 20 may be included in series with the direct current supply to prevent the building up of abnormally high voltages in the main transformer. The rectifier 7 may then be 90 started by supplying the necessary starting voltages to the starting electrodes through the switch 21 and transformer 22. As soon as the apparatus has begun to operate switch 18 may be thrown to contact 23 to disconnect resistance 20, switch 17 may be thrown to the position indicated to disconnect battery 16 and switch 21 opened. 95

The frequency of the oscillations produced may be determined by means of a 100 condenser 24 which is connected across a portion or the whole of, the primary winding 5. In the operation of a system of the type described it is necessary for efficient 105 and satisfactory operation that current should be allowed to start in one valve before it is completely interrupted in the other valve. This requires that the positive voltages supplied to the grids of the valves should lead the voltages induced in the 110

secondary 6. The desired lead in voltage may be secured by including a condenser or other capacitance means in circuit with the primary of transformer 9. In the arrangement shown in Fig. 1 this condenser 25 is connected to the circuit through a transformer 26 for the purpose of stepping down the current and thus permitting the use of a smaller condenser.

In order to secure the most satisfactory operation of a system of the type here involved it is necessary that momentary fluctuations in the direct current supplied during the periods when the current is being transferred from one valve to another should be prevented. This may be accomplished by inserting a reactance in series with the direct current supply which absorbs the difference of potential between the direct current supply source and the voltage across the transformer winding plus the drop in the valve. This reactance for low frequency use would have to be of the iron core type and if subjected to direct current saturation would have to be unduly large. It is also desirable to employ a reactance in the output circuit which reactance also, if subject to direct current saturation, would have to be large. It is possible, however, by combining these reactances 27 and 28 on a single core to greatly reduce the size required. The two reactances are so wound that the direct current components of the two currents flowing neutralize each other and these current components have no saturating effect upon the core.

The system which I have described is especially adapted for transforming high voltage direct current to direct current at a lower voltage, but may equally well be employed for producing the opposite result. It will of course be understood that the types of valve and rectifier indicated are purely illustrative and that other equivalent types may equally well be employed. The ratio between the voltage of the direct current supply and the voltage supplied to the load will be substantially equal to the ratio of the turns in the primary winding 5 to the turns in the secondary winding 6.

In order to obtain the most satisfactory operation of the valves 3 and 4, the controlling potentials applied to the grids should also be of substantially rectangular wave form. The potentials produced between the terminals of secondary 6 have the desired wave form but the use of the condenser 25 for obtaining the desired angle of lead tends to change the wave form so that the wave form of the potential applied to transformer 9 differs materially from that desired. The irregularity in wave form thus introduced is however corrected by the reactance 11 in the grid circuits so that the wave form applied to the grids may

be made to be substantially the same as that produced at the terminals of secondary 6.

In the arrangement shown in Fig. 2 the desired angle of lead is obtained by connecting a resistance 29 and reactance 30 in series across the terminals of secondary 6 and connecting the primary of transformer 9 to the terminals of reactance 30.

I have used the expression "substantially rectangular wave form" in this specification and in the claims which follows, not in its strict geometrical sense but to describe a wave which builds up to its maximum value and dies down much more rapidly than a sine wave, and has what is commonly known as a flat top.

What I claim as new and desire to secure by Letters Patent of the United States is:

1. The combination in a system of electrical distribution of a source of direct current, a primary winding connected to said source through an electric valve, a secondary winding inductively associated with said primary winding, means for controlling the action of said valve to supply to said

primary winding substantially rectangular wave form current impulses, and means for supplying to said valve control means from said secondary winding variable voltages the phase of which leads the voltages induced in said secondary winding.

2. The combination in a system of electrical distribution of a source of direct current, a primary winding connected to said source through an electric valve, a secondary winding inductively associated with said primary winding, means for controlling the action of said valve to supply to said primary winding substantially rectangular wave form current impulses, and a circuit connection which includes a capacitance for supplying to said valve control means from said secondary winding variable voltages the phase of which leads the voltages induced in said secondary winding.

3. The combination in a system of electrical distribution of a source of direct current, a primary winding connected to said source through a plurality of electric valves, a secondary winding inductively associated with said primary winding, means for controlling the action of said valves to produce in said secondary winding substantially rectangular wave form current impulses, and means for supplying to the control means of said valves from said secondary winding variable voltages, the phase of which leads the voltages induced in said secondary winding.

4. The combination in a system of electrical distribution of a source of direct current, a primary winding connected to said source through an electric valve, a secondary winding inductively associated with said primary winding, and means for controlling

- the action of said valve to supply to said primary winding substantially rectangular wave form current impulses and for supplying to said valve control means from said 5 secondary winding variable voltages the phase of which leads the voltages induced in said secondary winding.
5. The combination in a system of electrical distribution of a source of direct current, a primary winding connected to said source through a plurality of electric valves, a secondary winding inductively associated with said primary winding, means for controlling the action of said valves to produce 10 in said secondary winding substantially rectangular wave form current impulses, and means for supplying to the control means of said valves from said secondary winding variable voltages of substantially 15 rectangular wave form, the phase of which leads the voltages induced in said secondary winding.
6. An electrical apparatus comprising direct current terminals, a transformer provided with primary and secondary windings, electrical valve means provided with a cathode and anode connected between one of said terminals and said primary winding and with a grid for controlling the current 20 between said cathode and anode, a capacitance connected between said secondary winding and said grid, and means connected in circuit with said grid for neutralizing the effect of said capacitance on the wave 25 form of the potential applied to said grid through said secondary winding.
7. An electrical apparatus comprising direct current terminals, a transformer provided with primary and secondary windings, electrical valve means provided with a cathode and anode connected between one of said terminals and said primary winding and with a grid for controlling the current 30 between said cathode and anode, a capacitance connected between said secondary winding and said grid, and means connected in circuit with said grid for neutralizing the effect of said capacitance on the wave 35 form of the potential applied to said grid through said secondary winding.
8. An electrical apparatus comprising direct current terminals, a transformer provided with primary and secondary windings, electrical valve elements provided with cathodes and anodes connected between one of said terminals and said primary winding and with control grids, a condenser connected between said secondary winding and said grids, means connected in circuit with said grids for neutralizing the effect of said 40 condenser on the wave form of the potential applied to said grids through said secondary winding, and means connected between said windings for neutralizing momentary fluctuations in the current supplied through 45 said terminals when current is transferred from one valve to another.
9. An electrical apparatus comprising direct current terminals, a transformer provided with primary and secondary windings, electrical valve elements provided with cathodes and anodes connected between one of said terminals and said primary winding and with control grids, a condenser connected between said secondary winding and 50 said grids, means connected in circuit with said grids for neutralizing the effect of said condenser on the wave form of the potential applied to said grids through said secondary winding, and means connected between said windings for neutralizing momentary fluctuations in the current supplied through 55 said terminals when current is transferred from one valve to another.
- In witness whereof I have hereunto set my 60 hand this 12th day of July, 1923.

ALBERT H. MITTAG.
